US00D898772S

(12) **United States Design Patent** (10) **Patent No.:** **US D898,772 S**
McGinley et al. (45) **Date of Patent:** **** Oct. 13, 2020**

(54) **ENGINE COMPONENT**

- (71) Applicant: **Harley-Davidson Motor Company Group, LLC**, Milwaukee, WI (US)
- (72) Inventors: **Ben McGinley**, Glendale, WI (US); **Frank Savage**, Fox Point, WI (US); **Brad Richards**, Grafton, WI (US); **Chetan Shedjale**, Wauwatosa, WI (US); **Nathan Abplanalp**, Milwaukee, WI (US); **Stephen R. Collins**, Fond du Lac, WI (US); **Richard W. Elchert**, Mequon, WI (US); **Dane Schwegman**, Wauwatosa, WI (US); **Michael DeCaluwe**, Jackson, WI (US); **Brian Saita**, Milwaukee, WI (US); **Scott Matthews**, Franklin, WI (US)
- (73) Assignee: **Harley-Davidson Motor Company Group, LLC**, Milwaukee, WI (US)
- (**) Term: **15 Years**
- (21) Appl. No.: **29/728,411**
- (22) Filed: **Mar. 18, 2020**

(57)

CLAIM

We claim the ornamental design for an engine component, as shown and described.

DESCRIPTION

FIG. 1 is a top, front, right perspective view of the claimed design;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a rear elevation view thereof.

The claimed design is shown in solid lines in the drawings. The broken lines formed by equal length dashes shown in

(Continued)

the drawings are for the purpose of illustrating portions of the engine component that form no part of the claimed design.

1 Claim, 5 Drawing Sheets
